UNITED STATES PATENT OFFICE

HAROLD M. RUTH, OF HUNTINGTON PARK, CALIFORNIA

LOAD-EJECTING APPARATUS FOR CONVEYERS

Application filed June 6, 1928. Serial No. 283,370.

My invention relates generally to conveying machinery such as dredgers, excavators, elevators, loaders, trenchers, and conveyers of the character having buckets or scoops 5 in which loads of material are adapted to be transported from one place to another, and it is a purpose of my invention to provide an apparatus of simple and rugged construction by which loads of material in the buckets can be 10 positively ejected or discharged therefrom automatically and with the utmost ease and effectiveness so that the buckets will be completely emptied of the material and will again be ready for subsequent filling thereof with 15 other material to be transported.

It is a further purpose of my invention to provide a load ejecting apparatus which in its association with a conveyer or other form of conveying machinery embodying bucket 20 carrying endless chains or belts, is wholly independent thereof so that conventional forms of buckets and chains can be employed without modification of the construction thereof, and yet loads of material positively and automatically ejected from the buckets with the 25 utmost ease and dispatch at a predetermined point in the travel of the buckets.

I will describe only one form of load ejecting apparatus for conveyers embodying my 30 invention and will then point out the novel features in claims.

In the accompanying drawing

Fig. 1 is a view showing in side elevation a conventional type of excavator with one form 35 of load ejecting apparatus embodying my invention, applied thereto;

Fig. 2 is an enlarged fragmentary view in side elevation, of a portion of the excavator shown in Fig. 1, and illustrating the load 40 ejecting apparatus embodying my invention;

Fig. 3 is a sectional view taken on the line 3-3 of Fig. 2; and

Fig. 4 is a diagrammatic view illustrating a number of corresponding positions occupied 45 by a bucket of the excavator and an ejector member embodying my invention, during its operation of ejecting a load of material from the bucket.

Referring specifically to the drawing in 50 which similar reference characters designate

similar parts in each of the several views, my invention in its present embodiment is shown for the purpose of illustration only, applied to a conventional form of excavator including a suitable frame F on which is rotatably mounted a plurality of idler sprockets 10, 11, and 12, there being two of each (only one being shown) arranged in pairs in side by side spaced relation on shafts 13, 14 and 15 respectively, journaled in the lower end 55 of the frame F as shown.

Other sprockets 16 and 17, also two of each (only one sprocket 16 being shown) arranged in pairs in side by side spaced relation are fixed respectively to shafts 18 and 19 journaled in the upper end of the frame as shown. About the sprockets above described are adapted to be trained endless chains, designated at C and C', and secured to the chains between the latter at suitable equally spaced 65 intervals are buckets B of the scoop type.

The pair of sprockets 16 constitute driving sprockets, and their shaft 18 is adapted to be driven from a suitable source of power (not shown) to drive the chains C and C' in the 70 direction of the arrows, Figs. 1 and 2, to the end that with the frame F suitably supported in the position shown in Fig. 1, the buckets B will successively scoop up material from the excavation illustrated in this figure and 75 will elevate the material from the excavation. The general arrangement of excavator above described is well known in the art, and it is therefore believed that further detailed description and illustration thereof will be unnecessary as it forms no part of my present invention.

For the purpose of positively ejecting from the buckets, the loads of excavated material elevated by the buckets so that the buckets 80 will return empty into the excavation for subsequent filling, I provide the following apparatus which in its present embodiment broadly involves one or more ejector members 85 designated generally at E which utilize the pair of sprockets 17, broadly constituting a rotary element, as a means for mounting the members E for movement bodily with the sprockets and for movement independently of the sprockets by an actuating means desig- 90

nated generally at A, in such manner that the ejector members E are caused to enter and eject from the buckets B the loads of material elevated thereby.

In the present instance three ejector members E are shown, and all are of identical construction. Each of the ejector members comprises a rectangular metal plate 20 secured by rivets 21 to a pair of brackets 22 having sleeves 23 through which extends a shaft 24, to which the sleeves are secured by means of keys 25, to the end that the members will be fixed to the shaft. The shaft of each of the ejector members is of sufficient length to span the pair of sprockets 17 and is journaled at its ends in bearings 26 formed integral with the sprockets, the arrangement of the shafts of the three ejector members with respect to the sprockets being such that the ejector members are pivotally mounted on the sprockets at equally spaced intervals circumferentially of the sprockets and adjacent their peripheries as is clearly shown in Fig. 2.

The actuating means A for the ejector members comprises in the present instance a cam 27 having a hub 28 in which one end of the shaft 19 is journaled, and a peripheral cam surface 29 of the contour shown in Figs. 2 and 4, the hub 28 of the cam being secured by bolts 30 to the frame F, to the end that the cam will be fixed against movement and will be disposed at the outer side of one of the pair of sprockets 17. To one end of each of the shafts 24 is secured an arm 31 having journaled thereon at its free end a roller 32 constantly urged into engagement with the peripheral cam surface 29 of the cam 28 by a spring 33 connected at one end to the arm 31 and at its other end to one of the pair of sprockets 17, to the end that the ejector members E will be constantly urged to rock in one direction about their axes by the springs 33 and are adapted to positively be rocked in the reverse direction about their axes by the cam 28, in response to rotation of the sprockets 17.

The operation of the load ejecting apparatus is as follows:

Assuming that the shaft 18 is being driven in the direction to drive the chains C and C' and hence the buckets B carried thereby, in the direction of the arrows (Figs. 2 and 4), the relative spacing of the buckets and ejector members and their timed relation as well as the contour of the peripheral cam surface 29, is such that as each loaded bucket approaches the pair of sprockets 17 an ejector member E will be actuated by the cam to cause the forward edge 34 of its plate 20 to enter the bucket and move downwardly along its rear wall 35 behind the load of material, as the bucket advances, (see corresponding positions of the bucket and plate 20, numbered 1, 2, 3, 4, and 5 in Fig. 4) to thus scrape the material from the rear wall, the plate entering the bucket at a slight angle to the rear wall so as to act as a

wedge to shift the load of material forwardly in the bucket and thus loosen the material from the sides 36 and bottom 37 of the bucket. In this connection it will be noted that the sides and bottom of each bucket flare outwardly from its rear wall 35 so that once the material in the bucket has been shifted forwardly by the plate 20, the material will positively be loosened and its subsequent ejection greatly facilitated.

As the sprockets 17 continue to rotate and the bucket to advance in timed relation thereto, the cam 28 will rock the member to cause its plate 20 to sweep forwardly through the bucket as shown by corresponding positions of the bucket and plate, numbered 6 to 10 inclusive in Fig. 4, so as to positively eject the loosened load of material from the bucket, the material being completely ejected from the bucket while the latter is still occupying a downwardly and forwardly inclined position so as to utilize the force of gravity to aid in discharging the load of material from the bucket.

As the movement of the unloaded bucket continues around the pair of sprockets 17, the contour of the cam 28 is such as to permit the spring 33 of the particular ejector member which ejected the load of material from the bucket, to restore the ejector member to a position to enter the third succeeding bucket as it approaches the sprockets 17 and eject the load of material therefrom in the manner above described. As each bucket approaches the pair of sprockets 17, the load of material therein is positively ejected therefrom by one of the ejector members, so that the buckets will be emptied in successive order for subsequent filling upon their return to the excavation. It will be noted that the relation of the pair of driving sprockets 16 to the pair of sprockets 17 is such, that as a bucket approaches the latter sprockets, it moves towards the plate 20 of the particular ejector member which is to eject the load of material from the bucket, as the plate enters the bucket behind the load of material therein, so that the initial wedging action of the plate in loosening the material from the bucket is greatly expedited.

It will be manifest that my load ejecting apparatus is entirely physically independent of the chains C and C' and the buckets B carried thereby so that modification or complication of these parts to accommodate a load ejecting means is rendered unnecessary, thus permitting my load ejecting apparatus to be embodied in conventional chain and bucket construction, it being appreciated that the only modification of a conveyer necessary in order to apply my invention thereto, is in providing new sprockets 17 with my ejector members E mounted thereon, and in providing a suitable fixed support for the cam 28.

Although I have herein shown and de-

scribed only one form of load ejecting apparatus for conveyers embodying my invention, it is to be understood that various changes and modifications may be made therein without departing from the spirit of the invention and the spirit and scope of the appended claims.

I claim:

1. Apparatus of the character described comprising an ejector member, means for mounting the member independently of a conveyer bucket having a bottom wall, a rear wall and an open top and front, and a cam for actuating the member and having a contour such that during movement of the conveyer, the member will be caused to enter the open top of the bucket substantially edge-wise and move towards the bottom wall of the bucket between the rear wall thereof and a load of material therein, and to then eject the material forwardly from the bucket through its open front.

2. Load ejecting apparatus comprising a rotary element, an ejector member mounted on the rotary element for movement therewith and for movement independently of the rotary element, and a fixed cam for actuating the member during rotation of the rotary element, and being of a contour such as to move the member independently of the rotary element in such manner that the member is adapted to enter the open top of a bucket between the rear wall of the latter and a load of material therein and eject the material from the bucket.

Signed at Los Angeles in the county of Los Angeles and State of California this 23d day of May, A. D. 1928.

HAROLD M. RUTH.
